(57) **CLAIM**

The ornamental design for a remote control receiver which is connectable to a computer or an MP3 player device, as shown and described.

DESCRIPTION

FIG. 1 is a perspective view of a remote control receiver which is connectable to a computer or an MP3 player device showing my new design;

FIG. 2 is a left side elevational view thereof; the right side elevational view being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a front elevational view thereof in an alternate position of use;

FIG. 8 is a left side elevational view thereof; the right side elevational view being a mirror image;

FIG. 9 is a rear elevational view thereof;

FIG. 10 is a top plan view thereof; and,

FIG. 11 is a bottom plan view thereof.
